UNITED STATES PATENT OFFICE.

CLINTON E. WHITNEY, OF NEW YORK, N. Y., ASSIGNOR TO THE UNITED STATES BATTERY COMPANY, OF SAME PLACE.

DESIGN FOR A PORTABLE ELECTRIC LAMP.

SPECIFICATION forming part of Design No. 30,206, dated February 14, 1899.

Application filed January 16, 1899. Serial No. 702,369. Term of patent 7 years.

To all whom it may concern:

Be it known that I, CLINTON E. WHITNEY, a citizen of the United States, residing at New York, in the borough of Manhattan and State 5 of New York, have invented and produced a new and useful Design for Portable Electric Lamps, of which the following is a specification, reference being had to the accompanying drawing, forming a part thereof.

10 The drawing is a perspective view of a portable electric lamp, showing my design.

As shown in the drawing, the leading or material feature of my design consists of a tubular body part B, provided with screw- 15 caps C and C', and a reflector R, located on one side and near the center of the body part B.

L is an electric lamp located within the re-

flector, and A a rearward extension secured to the body part B substantially in alinement with the axis of the reflector R, S and S' being thumb-screws in the upper cap C and in the rearward extension A. 20

Having described my invention, what I claim as new, and desire to secure by Letters Patent, is—

25 The design for a portable electric lamp, as herein shown and described.

In testimony whereof I have hereunto subscribed my name this 12th day of January, 1899.

CLINTON E. WHITNEY.
